(57) **CLAIM**

The ornamental design for a display screen with graphical user interface, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever. The FIGURE illustrates a front view of a display screen with a graphical user interface.

The broken line of the display screen and the broken line showing of certain text and images in the drawing are for illustrative purposes only and form no part of the claimed design.

1 Claim, 1 Drawing Sheet The screenshot shows the MyInstrument software interface. At the top, there is a navigation bar with a home icon, a back arrow, and a search bar containing the text "Experiment - 2010-09-09 155752". Below the search bar is a question mark icon. The main workspace is titled "Select Sub Array" and contains a 4x3 grid of 12 empty boxes. To the left of this grid are labels for subjects 1 through 5 and sub-groups A, B, C, and D. Below the grid is a "Run" button. To the right of the array is a timeline titled "Select Cycle" with 48 numbered boxes. A legend indicates that solid lines represent "Heated cover reached target temperature" and dashed lines represent "Heated cover did not reach target temperature". A "Scheduler" button is located in the bottom right corner. In the top right corner, there is a copyright notice: "© 2011 Life Technologies".
